1

Common name: Apple.
Botanical classification: *Malus domestica* (Suclow Borkh).
Variety denomination: 'BENITSURUGI'.

CROSS-REFERENCE TO RELATED APPLICATION

This application claims priority of Japanese plant variety rights application No. 37015 filed Aug. 31, 2023, the entire content of which is incorporated by reference herein.

BACKGROUND OF THE NEW VARIETY

The present invention relates to a new and distinct variety of apple tree, *Malus domestica* (Suclow) Borkh, which has been given the variety denomination 'BENITSURUGI'.

ORIGIN OF THE VARIETY

The parent varieties are '5-12786' (male parent) (not patented) and 'SANSA' (female parent) (U.S. Plant Pat. No. 6,519), respectively.

The variety was developed and propagated at the Morioka Research Station, Institute of Fruit Tree and Tea Science,

(57) **ABSTRACT**

A new variety of apple tree 'BENITSURUGI' that has columnar tree type, bearing on spurs only, thick to very thick shoot thickness, short internode length, long leaf blade length, long petiole length, short to medium fruit stalk length, medium size and short to medium height fruit with fully open locules.

11 Drawing Sheets

2

National Agriculture and Food Research Organization (NARO), in Morioka, Iwate, Japan.

The variety was reproduced asexually by vegetative reproduction by grafting one-year-old cuttings on rootstocks.

In 2005, crossing the parent varieties and collecting seeds.

In 2006, columnar type's seedlings are selected by SCAR682 DNA marker from growing seedlings.

In 2007, they were grafted on JM1 root stock.

In 2008, they were transplanted at breeding field. And selected individual plant.

In 2015, the instant plant was selected as a promising breeding line and provisionally named 'Morioka 74'.

In 2016, growing test for local adaptability were started under confidentiality conditions at 16 public testing stations in Japan.

On Aug. 31, 2023, an application for plant variety rights No. 37015 was filed for the present variety in the Japanese Plant Variety Protection Office of the Ministry of Agriculture, Forestry and Fisheries (MAFF), Japan.

Cultivation of the variety does not require special conditions or treatments.

The variety is currently mainly intended for fruit production (table use).

SUMMARY OF THE VARIETY

The present variety is distinguished by columnar tree type, bearing on spurs only, thick to very thick shoot thickness, short internode length, long leaf blade length, long petiole length, short to medium fruit stalk length, medium size and short to medium height fruit with fully open locules, that distinguish it, notably from its male parent '5-12786' (medium extent of anthocyanin overcolor of young fruit, late harvest time) and female parent 'SANSA' (ramified tree type, medium shoot thickness, medium internode length, early harvest time), as well as from reference varieties 'SENSHU' (ramified tree type, bearing on spurs and long shoots, thin to medium shoot thickness, medium internode length, medium leaf blade length, short to medium petiole length, fruit with moderately open locules) and 'SHINANO SWEET' (ramified tree type, bearing on spurs and long shoots, thin to medium shoot thickness, medium internode length, short to medium leaf blade length, short to medium petiole length, medium to long fruit stalk length, large size and tall height fruit).

A comparison with the male parent '5-12786' is as follows (evaluation based on averages):

TABLE 1

No.	Characteristics	Male parent '5-12786' States	Present variety 'BENITSURUGI' States
34	Young fruit: extent of anthocyanin overcolor	medium	absent or very small to small
101	Time of harvest	late	medium

A comparison with the female parent 'SANSA' is as follows (evaluation based on averages):

TABLE 2

No.	Characteristics	Female parent 'SANSA' States	Present variety 'BENITSURUGI' States
2	Tree: type	ramified	columnar
9	One-year-old shoot: thickness	medium	thick to very thick
10	One-year-old shoot: length of internode	medium	short
101	Time of harvest	early	medium

A comparison with the reference varieties 'SENSHU' and 'SHINANO SWEET' is as follows (evaluation based on averages):

TABLE 3

No.	Characteristics	Reference variety 'SENSHU' States	Reference variety 'SHINANO SWEET' States	Present variety 'BENITSURUGI' States
2	Tree: type	ramified	ramified	columnar
6	Tree: type of bearing	on spurs and long shoots	on spurs and long shoots	on spurs only
9	One-year-old shoot: thickness	thin to medium	thin to medium	thick to very thick
10	One-year-old shoot: length of internode	medium	medium	short

TABLE 3-continued

No.	Characteristics	Reference variety 'SENSHU' States	Reference variety 'SHINANO SWEET' States	Present variety 'BENITSURUGI' States
15	Leaf blade: length	medium	short to medium	long
16	Leaf blade: width	narrow to medium	narrow to medium	medium to broad
22	Petiole: length	short to medium	short to medium	long
23	Petiole: extent of anthocyanin coloration from base		medium	small
15	Flower: predominant color at balloon stage		light pink	dark pink
30	Young fruit: extent of anthocyanin overcolor	large		absent or very small to small
61	Fruit: size		large	medium
62	Fruit: height		tall	short to medium
86	Fruit: length of stalk	medium	medium to long	short to medium
25	Fruit: aperture of locules (in transverse section)	moderately open		fully open
98	Time of harvest		medium to late	medium

BRIEF DESCRIPTION OF THE DRAWINGS

In the accompanying drawings, which are as nearly true as is reasonable possible to make in a color illustration of this type:

FIG. 1 is a color photograph showing a general view of the apple tree named 'BENITSURUGI' at harvest time.

FIG. 2 is a color photograph showing a flower of 'BEN-
ITSURUGI'.

FIG. 3 is a color photograph showing detached upper surface petals, pistils, flowering stalk including calyx and detached stamens of the flower of 'BENITSURUGI'.

FIG. 4 is a color photograph showing fruits of 'BEN-
ITSURUGI'.

FIG. 5 is a color photograph showing cross sections of fruits of 'BENITSURUGI'.

FIG. 6A is a color photograph showing the tree type of reference variety 'SHINANO SWEET'.

FIG. 6B is a color photograph showing the tree type of reference variety 'SENSHU'.

FIG. 6C is a color photograph showing the tree type of the present variety 'BENITSURUGI'.

FIG. 7 is a color photograph showing one year old shoot of 'BENITSURUGI' (top), in comparison with 'SENSHU' (middle) and 'SHINANO SWEET' (bottom).

FIG. 8 is a color photograph showing leaves of 'BEN-
ITSURUGI' (center), in comparison with 'SHINANO
SWEET' (left) and 'SENSHU' (right).

FIG. 9A is a color photograph showing the petiole: extent of anthocyanin coloration from base of 'BENITSURUGI' (bottom), in comparison with 'SHINANO SWEET' (top).

FIG. 9B is a color photograph showing a more detailed view of the petiole: extent of anthocyanin coloration from base of 'BENITSURUGI' (bottom), in comparison with 'SHINANO SWEET' (top).

FIG. 10 is a color photograph showing the flower bud of 'BENITSURUGI' (left), in comparison with 'SHINANO SWEET' (right).

FIG. 11 is a color photograph showing the young fruit of 'BENITSURUGI' (left), in comparison with 'SENSHU' (right).

FIG. 12 is a color photograph showing the fruit of 'BENITSURUGI' (center), in comparison with 'SHINANO SWEET' (top) and 'SENSHU' (bottom).

FIG. 13 is a color photograph showing another view of the fruit of 'BENITSURUGI' (center), in comparison with 'SENSHU' (left) and 'SHINANO SWEET' (right).

FIG. 14 is a color photograph showing the underside of fruit of 'BENITSURUGI' (middle), in comparison with 'SHINANO SWEET' (top) and 'SENSHU' (bottom).

FIG. 15 is a color photograph showing the fruit stalk of 'BENITSURUGI' (center), in comparison with 'SENSHU' (left) and 'SHINANO SWEET' (right).

FIG. 16 is a color photograph showing the fruit shape of core of 'BENITSURUGI' (middle), in comparison with 'SHINANO SWEET' (top) and 'SENSHU' (bottom).

FIG. 17 is a color photograph showing the aperture of locules in transverse section of the fruit of 'BENITSURUGI' (right), in comparison with 'SENSHU' (left).

FIG. 18 is a color photograph showing a general view of the fruit of 'BENITSURUGI'.

Due to chemical and/or digital development, processing and printing, the plants or portions of plants depicted in the photographs may or may not be precisely accurate, when compared to the actual botanical specimens.

DETAILED DESCRIPTION OF THE INVENTION

The botanical description and the photographs are of the 'BENITSURUGI' plants evaluated from 2020 to 2022 (including for the comparison with the reference plants 'SENSHU' and 'SHINANO SWEET'. The age of the plants shown on the photographs and evaluated was 8 years, 5 months on Oct. 2, 2020. Values as provided are averages.

The plants shown on the photographs were grown at Morioka, Iwate, Japan.

The dates each photograph was taken are as follows:

FIGS. 1, 18: Oct. 2, 2020,

FIGS. 2, 3: May 11, 2020

FIGS. 4, 5: Oct. 9, 2020

FIGS. 6A, 6B, 6C: Sep. 29, 2022

FIG. 7: Dec. 23, 2022

FIGS. 8, 12, 16: Dec. 15, 2022

FIG. 9A, 9B: Aug. 24, 2020

FIG. 10: May 10, 2021

FIG. 11: Jun. 21, 2021

FIGS. 13, 14, 15, 17: Dec. 1, 2021

Colors are given according to The R.H.S. (Royal Horticultural Society) Colour Chart, Sixth Edition, 2015.

BOTANICAL DESCRIPTION

TABLE 4-continued

No.	Characteristics	States	Values
4	Tree: average spread		1.2 m
5	Tree: habit	not applicable	
6	Tree: type of bearing	on spurs only	
7	Tree: trunk color	medium brown	166B
8	Tree: bark surface texture	smooth-medium	
9	One-year-old shoot: thickness	thick to very thick	8.2 mm
10	One-year-old shoot: length of internode	short	1.2 cm
11	One-year-old shoot: color on sunny side	medium brown	200A (dark brown)
12	One-year-old shoot: pubescence (on distal half of shoot)	strong	
13	One-year-old shoot: number of lenticels	many	
14	Leaf blade: attitude in relation to shoot	outwards	
15	Leaf blade: length	long	11.5 cm
16	Leaf blade: width	medium to broad	6.6 cm
17	Leaf blade: ratio length/width	medium to large	1.7
18	Leaf blade: intensity of green color (upper surface)	dark green	139A
19	Leaf blade: intensity of green color (lower surface)	light green	142C
20	Leaf blade: incisions of margin (upper half)	serrate type 2 (crenate to serrate)	
21	Leaf blade: pubescence on lower side	medium	
22	Petiole: length	long	4.6 cm
23	Petiole: extent of anthocyanin coloration from base	small	22.50%
24	Petiole: color	light green	145C
25	Leaf stipule: length	11.0 mm	
26	Leaf stipule: width	2.5 mm	
27	Leaf stipule: shape	long round	
28	Leaf stipule: color	medium green	143B
29	Flowers: average number per spur	5 flowers per cluster	
30	Flower: predominant color at balloon stage	purplish pink	N74C
31	Flower: diameter with petals pressed into horizontal position	small to medium	4.8 cm
32	Flower: arrangement of petals	overlapping	
33	Flower: position of stigmas relative to anthers	same level	
34	Young fruit: extent of anthocyanin overcolor	absent or very small to small	10.70%
35	Sepal: length		8.6 mm
36	Sepal: width		5.0 mm
37	Sepal: shape	deltoid	
38	Sepal: surface texture	smooth with medium pubescence	
39	Sepal: color	light green	141D
40	Pedicel: length		16.3 mm
41	Pedicel: width		2.1 mm
42	Pedicel: surface texture	smooth with medium pubescence	
43	Pedicel: color	medium brown green	146D
44	Reproductive organs: number of stamens per flower		20
45	Reproductive organs: number of styles per flower		5
46	Reproductive organs: length of stamen		8.4 mm

TABLE 4-continued

No.	Characteristics	States	Values	
47	Reproductive organs: length of anther		2.7 mm	5
48	Reproductive organs: length of style		6.2 mm	
49	Reproductive organs: color of filament	white	155A	
50	Reproductive organs: color of anther	light yellow	5D	
51	Reproductive organs: color of style	light green	145B	
52	Reproductive organs: color of stigma	light green	144D	
53	Reproductive organs: color of ovary	light green	145B	
54	Seed: number per fruit		8.6	
55	Seed: number per fruit cell		1.6	
56	Seed: length		8.3 mm	
57	Seed width		4.8 mm	
58	Seed: depth		3.3 mm	
59	Seed: shape	obtuse		
60	Seed: color (with RHS number)	dark brown	187A	
61	Fruit: size	medium	311.5 g	
62	Fruit: height	short to medium	8 cm	
63	Fruit: diameter	medium	9.1 cm	
64	Fruit: ratio height/diameter	medium	0.88	
65	Fruit: general shape	globose		
66	Fruit: ribbing	absent or weak		
67	Fruit: crowning at calyx end	absent or weak		
68	Fruit: size of eye	very small to small		
69	Fruit: length of sepal	short to medium		
70	Fruit: bloom of skin	absent or weak		
71	Fruit: greasiness of skin	absent or weak		
72	Fruit: surface texture of skin	smooth		
73	Fruit: ground color	yellow green	150C (yellow green) 87.7%	
74	Fruit: relative area of over color	large		
75	Fruit: hue of over color-with bloom removed	red	187B (dark purple red)	
76	Fruit: intensity of over color	dark		
77	Fruit: pattern of over color	solid flush with weakly defined stripes		
78	Fruit: width of stripes	narrow to medium		
79	Fruit: intensity of stripes	weak to medium		
80	Fruit: area of russet around stalk attachment	absent or small		
81	Fruit: area of russet on cheeks	absent or small		
82	Fruit: area of russet around eye basin	absent or small		
83	Fruit: number of lenticels	medium		
84	Fruit: size of lenticels	small to medium		

TABLE 4-continued

No.	Characteristics	States	Values
85	Fruit: scarfskin	very small to small	
86	Fruit: length of stalk	short to medium	1.8 cm
87	Fruit: thickness of stalk	thin to medium	3.1 mm
88	Fruit: depth of stalk cavity	shallow medium	2.2 cm
89	Fruit: width of stalk cavity	narrow medium	4 cm
90	Fruit: depth of eye basin	medium	1.2 cm
91	Fruit: width of eye basin	medium	3.4 cm
92	Fruit: firmness of flesh	medium	15 lbs
93	Fruit: color of flesh	cream	8D (light yellow)
94	Fruit: sweetness of flesh	medium	13.5 %
95	Fruit: acidity of flesh	low	0.36 g/100 ml
96	Fruit: water-core of flesh	absent or very slight	
97	Fruit: shape of core	flat round	
98	Fruit: aperture of locules (in transverse section)	fully open	
99	Pollination requirements	flowers are self-incompatible, S genotype is S3S5 and requires pollination by another S genotype diploid apple	
100	Time of beginning of flowering	early to medium	May 9
101	Time of harvest	medium	October 2
102	Shipping quality	moderate	
103	Storage life	6-11 days at room temperature, 1 month at refrigerated temperature	
104	Market use	fresh, juice, multiple use	
105	Productivity (weight/plant)		22.5 kg/tree (average for 7-8 year-old tree)
106	Resistance to: Alternaria blotch	strong	

Other features of the plant are as follows:

Disease resistance: Resistance to *Alternaria* blotch (*Alternaria alternata*) was observed. The new variety has the same susceptibility to Blotch (*Diplocarpon mal*), Powdery mildew (*Podosphaera leucotricha*) and Scab (*Venturia inaequalis*) as existing cultivars.

I/we claim:

1. A new and distinct variety of apple tree named 'BEN-ITSURUGI', substantially as described and illustrated herein.
